FIG. 2.

FIG. 1.

FIG. 3.

INVENTOR
Warren Clemens

BY *Harold V. Stonebraker*

ATTORNEY

UNITED STATES PATENT OFFICE

2,066,251

DRIER

Warren Clemens, Pavilion, N. Y.

Application October 25, 1935, Serial No. 46,751

1 Claim. (Cl. 34—38)

This invention relates to a drier, and has for its object more particularly to afford an apparatus of economical construction and simple in its operation and control, for the drying of beans or other materials.

In a more specific aspect, the invention has for its purpose to afford an efficient arrangement that will dry beans effectively and thoroughly, at the same time preventing drying at such a speed as would be detrimental to the product.

A further purpose is to afford an apparatus in which the beans are properly agitated and caused to travel through the drier by gravity, in a manner that subjects them to increasing heat as they progress through the machine and their moisture is exhausted.

To these and other ends, the invention consists in the arrangement and construction of parts that will appear clearly from the following description when read in conjunction with the accompanying drawing, the novel features being pointed out in the claim at the end of the specification.

In the drawing:

Fig. 1 is a vertical sectional view of a drying apparatus constructed in accordance with a preferred embodiment of the invention;

Fig. 2 is a partial side elevation, and

Fig. 3 is a horizontal sectional view taken on the line 3—3 of Fig. 1.

Referring more particularly to the drawing in which like reference characters refer to the same parts throughout the several views, the structure comprises a supporting frame including uprights 1 and horizontal connecting portions 2, and within this supporting frame is arranged a gravity conveyor that is constructed in the following manner.

3 designates a housing that is preferably rectangular in cross-section as shown, and is arranged vertically within the supporting frame, said housing being carried by a series of leaf spring members or flexible metal bars 4, the upper end of each of which is fixedly connected to one of the cross members 2 of the supporting frame, while the lower end of each leaf spring member 4 is rigidly connected to the adjacent side wall of the housing 3.

Preferably there are two sets of such spring supporting elements, one at the top of the housing 3 and one at the bottom thereof, and it will be observed that these spring members 4 suspend the housing 3 from the supporting frame and hold it firmly in place, affording a stiff but yielding suspension, the resiliency of the spring

members 4 being such as to permit the necessary back and forth horizontal movement of the housing 3, which is imparted in a manner that will be described presently.

The housing 3 is provided interiorly with a series of perforate baffles 5 and 6, which may be of sheet metal or wire screen material, or otherwise constructed to support the material passing through and to permit movement of air upwardly through the baffles for drying. The baffles 5 and 6 are arranged in staggered relation and inclined preferably at about the angle shown, each baffle terminating at its lower end at a point spaced from but in close proximity to the adjacent wall of the housing and to the adjacent portion of the baffle immediately below.

This arrangement of the baffles causes the desired continuous movement of the product to be dried from top to bottom and at the same time prevents the passage of any substantial proportion of the upwardly moving air around the ends of the baffles and forces such air currents to travel through the central portions of the baffles and thereby to impart a maximum drying effect to the beans or other material traveling downwardly.

The housing is provided with an inlet opening 7 and hopper 8 at the top through which the beans or other material is fed into the drier and an outlet 9 at the bottom from which they are delivered into any suitable receptacle. 10 designates an air inlet at the bottom of the housing, the same being connected by a flexible joint 11 with a conduit 12 into which heated air is forced from any convenient source of supply. 13 designates a vertical deflector at the bottom of the housing to direct the incoming current of air upwardly through the horizontal baffles 5 and 6, while 14 designates an air outlet provided at the top of the housing through which the damp cool air is exhausted.

The housing 3 is actuated back and forth during the drying operation by any suitable mechanism, in order to impart a shaking action to the baffles and cause the beans or other material to travel by gravity over the several baffles successively from the top to the bottom of the housing. This may be accomplished by a vertically arranged rotatable shaft 15 suitably journaled on the supporting frame 1 in parallel relation to the housing 3 and provided with a pulley 16 to which a belt may be applied for rotating the shaft 15. 17 designates a plurality of cranks pivotally connected to a side wall of the housing 3 and operatively associated with the shaft 15 by means of 55

eccentrics 18, or otherwise, so that rotation of the shaft 15 imparts the necessary horizontal back and forth movement to the housing 3. 19 5 designates a series of pivoted doors in a side wall of the housing to permit access, when desired, to the interior thereof and to the spaces between the adjacent baffles 5 and 6 for cleaning or repairing the baffles, or otherwise as needed.

It will be understood that when the drier is in 10 operation, the housing 3 and with it the baffles 5 and 6 are moved back and forth in a generally horizontal direction while supported on the spring members 4, and during this shaking movement of the housing and baffles, the beans or other material introduced through the inlet 1, travel 15 downwardly through the housing over the baffles 5 and 6 alternately, passing outwardly through the opening 9 at the bottom of the housing. At the same time, air is forced into the bottom of 20 the housing through the opening 10 and travels thence upwardly through the central zones of the baffles and outwardly at the opening 14 at the top of the housing.

With this arrangement, the beans as they 25 enter the machine when in their dampest condition first contact with the coolest air, and as they travel downwardly and become drier, they meet currents of air which are increasingly hotter and drier, the driest beans being met at the bottom of 30 the housing by the air in its hottest and driest condition. With this arrangement and procedure, slow drying of the beans is assured, that is to say, they are not subjected when in a damp state to excessively hot air that would otherwise 35 split, damage, or deteriorate the product, and when the beans emerge from the bottom of the housing, they are thoroughly dried. The struc-

ture permits a continuous operation at a low cost, and requires little attention on the part of the operator.

While the invention has been described with reference to a particular embodiment, it is not confined to the details shown and described, and this application is intended to cover such modifications as may come within the contemplated purposes of the improvement or the scope of the following claim.

I claim:

A drier comprising a supporting frame including uprights and horizontal connecting portions spaced one above the other, of a housing closed on four sides and inclined perforate baffles arranged in staggered relation in said housing one above the other, each of said baffles extending along three walls of the housing and being spaced from one wall thereof, said housing having an inlet at the top and an outlet at the bottom for material to be dried and an air inlet at the bottom, a source of hot air supply, a flexible connection between said source of hot air supply and said air inlet, leaf spring suspension members rigidly attached to said horizontal connecting portions of the frame and having their lower ends rigidly attached to the housing at points near the top and bottom thereof, said leaf spring members being relatively short and disposed with their flat surfaces at right angles to the direction of movement of the housing, a vertically disposed rotary shaft mounted on said supporting frame, and operating means connecting said shaft with the housing at points near the top and bottom of the latter for imparting horizontal movement thereto.

WARREN CLEMENS.
